MULTIPLE USE MAILING FOLDER

Le Roy Welliver, St. Paul, and Hugh H. Sievers,
Minneapolis, Minn.

Application July 18, 1941, Serial No. 402,932

1 Claim. (Cl. 229—73)

This invention relates to mailing cards and more particularly to a mailing card which is adaptable for several mailings.

It is a general object of our invention to provide a multiple mailing card which can be sent to an addressee and which can be folded by the addressee and returned to the original sender with an enclosure, and wherein a portion of the card can be detached and remailed to the original addressee, the detached card serving as a receipt and the like.

Another object of the invention is to provide novel means for folding and refolding the device and providing portions thereof with the addresses of the sender and the addressee so that in such folding and refolding either of the addresses can be visibly displayed and the writing of addresses by the addressee rendered unnecessary.

A more specific object of the invention is to provide a device which can be economically made from a single blank of paper and which when folded into its various forms can be conveniently secured together so that it will have much the appearance of the ordinary envelope.

These and other objects and advantages of the invention will more fully appear from the following description made in connection with the accompanying drawings, wherein like reference characters refer to the same parts throughout the views, and, in which:

Fig. 1 is a plan view of a form of our invention with the blank stamped out but unassembled;

Fig. 2 is a plan view of the device showing it ready for use;

Fig. 3 is a plan view of the device completely folded with the name of the addressee exposed;

Fig. 4 is a section on the line 4—4 of Fig. 3;

Fig. 5 is a plan view of the device arranged for return to the sender;

Fig. 6 is a section taken on the line 6—6 of Fig. 5;

Fig. 7 is a plan view of a modified form of the device showing it ready for folding and mailing;

Fig. 8 is a plan view of the construction in Fig. 7 as folded prior to mailing;

Fig. 9 is a section on the line 9—9 of Fig. 8;

Fig. 10 is a plan view of the device in Fig. 7 as refolded for return to the sender;

Fig. 11 is a section on the line 11—11 of Fig. 10;

Fig. 12 is a plan view of an unfolded blank embodying the invention in a different form;

Fig. 13 is a plan view of the device in Fig. 12 ready for mailing by the original sender;

Fig. 14 is a plan view of the device refolded for return to the sender; and

Fig. 15 is a section on the line 15—15 of Fig. 14.

In the drawings there is shown a card A which is provided with a series of transverse fold lines 16, 17 and 18, which divide the card A into a series of panels 19, 20, 21 and 22. The panel 19 is

folded upon the panel 20 along the scored line 16 and said panel 19 has gummed portions 23 which permit it to be secured adhesively to said panel 20, thus forming a pocket. Panel 21 is adapted to be folded at the line 17 downwardly against either side of the pocket formed by panels 19 and 20. Panel 22 is adapted to be folded along the line 18 downwardly against either side of the panel 21. Panel 22 adjacent the score line 18 is provided with a gummed strip 24, and on the side of the panel 22 having the gummed portion is an address panel 25 which is adapted to carry the address of the addressee and which is also adapted to register with a window 26 in the panel 21 when said panel 22 is folded downwardly thereagainst. The opposite side of the panel 22 is provided with an address space 27 which is adapted to receive the name of the original sender and when panel 22 is folded down against the other side of the panel 21 the address of the sender is visible through the window 26.

In Figs. 3 and 4 the device is shown folded for its original mailing. The panels 19 and 20 have previously been folded together and secured to form the pocket described above, and the panels 21 and 22 have been folded together with the faces shown in Fig. 1 against each other. The panels 21 and 22 are then folded as a unit on the score line 17 to bring the panel 22 between the pocket formed by panels 20 and 23 and the window panel 21. A small sticker 28 is then placed to connect the edges of panels 21 and 20 which lie at the score lines 18 and 16, and the name and address of the original addressee are visible through the window 26.

A device of this kind can be used, for example, by insurance companies, the company mailing out the card when folded as in Fig. 3 and one or more of the panels constituting a notice of the amount of premium used. The pockets formed by 19 and 20 can be used by the receiver of the notice to hold his remittance and then the device can be refolded to be returned to the company. When this is done the panel 22 is folded oppositely from the original folding thereof to bring the sender's return address space 27 in registry with the window 26 to be viewed therethrough, and panels 21 and 22 as a unit are folded forwardly as viewed in Fig. 2 and downwardly over the panel 20 of the pocket. The strip of adhesive 24 on the panel 22 is then moistened and secured to the lower edge of panel 20. A stamp can be placed in the upper right-hand corner of the panel 21 and the article can be returned to the company.

When received by the company the panel 22 is detached and the company address panel 27 is obliterated and a stamp placed on the opposite face of the panel, and this card is again mailed to the original addressee with a receipt or other

acknowledgement thereon, thus completing the cycle of transmittals which complete the particular transaction.

Another embodiment of the invention is shown in Fig. 7 through 11. In Fig. 7 there is shown a blank B which is made up of a plurality of foldable panels 29, 30, 31 and 32. The panel 29 has a window 33 and a cut-out notch 34 in an edge thereof. Panel 29 is folded up against the panel 30 and secured thereto by strips of adhesive 35. The panel 31 is provided with a pair of adhesive strips 36 and the panel 32 is provided with an addressee name space 37.

As viewed in Fig. 8 the device is folded as it should be for the original mailing to the addressee. The panel 32 has previously been folded backwardly against the panel 31 as viewed in Fig. 7. At the edges where the panels 31 and 32 are joined the panels are fed into the pocket formed by panels 29 and 30, and when they have been fully inserted into this pocket the addressee indicia at 37 will appear visible in the window 32. This exposes the word "pull" shown at 33 and through the cut-out notch 34 as best indicated in Fig. 8.

When the device is received by the addressee he pulls the panel 32 and panel 31 out of the pocket or envelope formed by panels 29 and 30 to read the printed matter on the inside of the card unit. He then folds the upper panel 32 forwardly against the panel 31. The two panels are then folded forwardly and downwardly against the panel 29 and panel 31 is secured to panel 29 by the adhesive strip 36. In Fig. 10 the rear side of panel 31 when folded downwardly over panel 29 bears the address of the original addressee and it is in condition for mailing to the addressee. When this is received by the original sender the device can be opened up, the enclosure taken from the pocket formed by panels 29 and 30, and the panel 32 detached from panel 31 so that said panel 32 can be again mailed to the original addressee as a receipt.

Figs. 12 through 15 illustrate another form of the invention. There is shown a blank C which, although considerably different in shape from the first two blanks, is one which is capable of the same uses as the other devices. There is shown a rear panel 39, a main front panel 40, an auxiliary front panel 41, a laterally extending panel 42 and a slotted tongue 43 which projects from the opposite side of the main rear panel 39 relative to the panel 42.

The lower panel 40 is adapted to fold upwardly against the rear panel 39, and the upper auxiliary front panel 41 is adapted to fold downwardly over the upper edge of the panel 40. This, however, is done only after the laterally extending panel 42 has been folded on the line 44 and the tongue 43 has been inwardly folded so that the end of the panel 42 can extend through the slot 45 in said tongue 43. This arrangement of the device C is illustrated in Fig. 13 and the auxiliary front panel 41 is connected to the larger front panel 40 by means of a suitable sticker 46. When thus arranged the device is shown in Fig. 13 addressed to the original addressee with the return address of the addressee in the upper left-hand corner.

When the device is received by the original addressee he breaks the seal 46 and can then unfold the article to read its contents. If a re-

mittance is to be made the panels 40 and 41 are first folded against the rear panel 39 and the remittance placed between the front and rear panels. Then the tongue 43 is folded over the front panels and tongue 42 folded over these panels from the other side with the end of the panel 42 extending into the slot 45 in the tongue 43, as shown in Fig. 14. Panel 42 and tongue 43 may be connected by placing the postage stamp 47 over the adjoining portions of the panel and tongue or the stamp may be placed in its usual position and a seal used to connect these two members 42 and 43. Then when the article has been returned to the original sender it can be opened up and the remittance removed therefrom. The laterally extending panel 42 is then detached along the score line 48 shown in Fig. 12, and said panel 42 is receipted and returned to the original addressee, the name of the original sender having been marked out where it is located in the delivery address position shown in Figs. 12 and 14, the reverse side of panel 42 being addressed to the original addressee.

From the foregoing description it will be seen that we have provided a multiple use stationery device which can be folded in various ways to present different addresses to view and wherein the device can be used as a means of transmitting statements and returning remittances. An additional use of the device is as a return receipt which constitutes a severable portion of the main blank. Thus the device is one which is capable of use for three different mailings.

Our invention is one which can be cheaply constructed from a single blank of sheet material and when folded for mailing is very similar to a conventional envelope both in size and shape.

A device of this type is of advantage in connection with the mailing of statements, return of remittances, and final mailing of receipts since the entire record of various transactions is retained on the single blank, and when the return receipt has been severed and mailed to the original addressee the remainder of the blank remains in the hands of the original sender as a record of the entire transaction. This saves considerable time in looking up files and other records as the various portions of the transaction are taken care of.

It will, of course, be understood that various changes may be made in the form, details, arrangement and proportions of the various parts throughout the views without departing from the scope of our invention.

What is claimed is:

In a multiple use mailing folder, an elongated strip of sheet material having transverse fold lines dividing said strip into a plurality of panels, two of said panels being folded against each other and secured at certain of their edges to form a pocket, the panel next to said pocket panels having a window formed therein, and a panel immediately adjacent said windowed panel having on opposite sides thereof an original address and a return address, said last mentioned panel being foldable alternately against opposite sides of said windowed panel and said original and return addresses being alternately visible through said window.

LE ROY WELLIVER.
